UNITED STATES PATENT OFFICE.

RAYMOND G. LAWRY, OF CHICAGO, ILLINOIS, ASSIGNOR TO ROBERTS & SCHAEFER COMPANY, OF CHICAGO, ILLINOIS, A CORPORATION OF ILLINOIS.

COMBINED SCREEN AND PICKING-TABLE.

1,381,204.

Specification of Letters Patent. Patented June 14, 1921.

Application filed April 30, 1920. Serial No. 377,836.

To all whom it may concern:

Be it known that I, RAYMOND G. LAWRY, a citizen of the United States, residing at Chicago, in the county of Cook and State of Illinois, have invented a certain new and useful Improvement in Combined Screens and Picking-Tables, of which the following is a specification.

My invention relates to improvements in combined screen and picking tables and used in connection with coal and the like handling and separating devices.

My device is peculiarly adapted for use in connection with the Marcus screen, but of course can be advantageously used in connection with many other types of screens and coal and material handling apparatuses.

Experience has shown that about 5 feet is the maximum permissible width for a jiggling table, because if the width is greater than that then the operator begins to have a great deal of trouble reaching over and getting at the material to pick the refuse as the material goes by, and in the past the capacity of screening plants has been limited by this limitation on the width of the screen and picking table.

By my invention I propose to obviate this difficulty by dividing the large sized screen into a plurality of separate smaller combined screens and picking tables which will all be in parallelism with one another and each one of these small screens will be of such size that the operator can easily reach far enough to do effective picking.

In the modified form shown in Figure 6, I show a section of a screen wherein the upper and the lower surfaces are separately hung.

My invention is illustrated more or less diagrammatically in the accompanying drawings, wherein:

Fig. 1 is a diagrammatic plan view;

Fig. 2 is a side elevation;

Fig. 3 is a section along the line 3—3 of Fig. 1;

Fig. 4 is a section along the line 4—4 of Fig. 1;

Fig. 5 is a section along the line 5—5 of Fig. 1;

Fig. 6 is a detailed section through a slightly modified form of the screen;

Fig. 7 is the driving head by which the upper and lower screen branches move in opposite direction so that they are in balance and the work done by the driving apparatus is reduced.

Like parts are indicated by like characters in all the figures.

A is a chute through which coal from the mine is discharged on to my screen table. A¹ is the screen table. It is supported on pivoted hangers A²—A² and is adapted to be oscillated by an eccentric driving head A³ driven from any suitable source of power.

The screen frame is made up of a solid bottom B having upwardly extending side walls B¹. These side walls support the screen B², the idea being that the material as the screen is reciprocated will pass down along the screen, the fine particles passing through the screen into the lower floor, the coarse particles passing along over the screen. It will be understood that the screen is not continuous throughout the entire length of the apparatus.

At the upper end the screen is of considerable width. The width is so great that the operator cannot reach far enough in to do satisfactory work. This wide part of the screen is indicated at C. Slightly removed from the head end the wide screen is separated into two relatively narrow branches C¹, C², there being a space between them sufficiently great for a man to stand and work.

The upper end of this space is bounded by two inclined walls C³—C³ so that the coal or similar material will be gradually deflected into the two branches of the screen. In order that this deflection or guiding of the coal may be assisted the upper surface of the two branch screens is outwardly inclined as at C⁴—C⁴, being a slight drop from the flat level screen surface shown at C⁵.

After the material has gotten well going on the two branches of the screen, it is not necessary to have the inclined surfaces and the screen surfaces are again horizontal as indicated in Fig. 5, there being a sudden drop of a short distance between the high portions of the inclined screen and the level screen as indicated at C⁶.

In the form which I have illustrated there are three separate screening portions in the

general screen plan, the first one at B² in the broad screen portion before the branches are reached, the second at D¹—D¹, in each of the two screen branches. After the coal has 5 passed over the second screen, the picking will be substantially finished and the screen branches will discharge into the main broad screen or conveyer by which the coal is carried away to be discharged into the chutes 10 D²—D³, which take the fine and the coarse particles respectively.

It will be evident that I have shown in my drawings an operative device, still many changes might be made both in size, shape 15 and arrangement without departing from the spirit of my invention, and I wish therefore that my drawings be taken as in a sense, diagrammatic.

The use and operation of my invention are 20 as follows:

The coal is fed down to the conveyer and screen as shown. As it comes on the screen it passes over the open screen floor and much of the fines will have an opportunity to pass 25 through leaving the coal in a relatively clean condition. This partly separated coal then passes on across a smooth continuous surface being divided into two or more separate streams by the separate branch arrangement 30 as shown and the pickers who will stand on both sides of each branch of the screen will be able to pick out rock, refuse and the like owing to the fact that the branches are narrow enough for the picker to reach in to do 35 his work. This work, of course, is made easier by the fact that much of the fine material which would otherwise interfere with the picking has already been screened out as above indicated.

40 The coal passes on down through the various branches to the next screen opening and since the coal will have been more or less disturbed by the picking and by the movement, more of the fine material will 45 have an opportunity to pass down through the screen to join the material from the screen above. The two streams of material then pass on carried by the movement of the screen until they are discharged through 50 the separate chutes as shown, one of which takes the fine, the other of which takes the coarse coal.

I have not indicated or discussed the treatment of the refuse picked out. Any 55 suitable conveyers can be provided for this refuse, and they form no part of my invention.

60 In the modified form which I have illustrated more or less diagrammatically the upper and lower screen portions are separate, but arranged one above the other and in this case, while they operate in exactly the same manner as before, if the driving head drives the upper part and the lower part in opposite

directions the screen assembly will be counterbalanced and less power will be required, and less vibration will result from the operation of the screen. 65

I claim:

1. A picking table having at both ends 70 relatively wide conveying surfaces and intermediate such wide surfaces having a plurality of separate narrow conveying surfaces arranged in parallel, there being sufficient space between the narrow surfaces to 75 permit an operator to stand and work between them.

2. A picking table having at both ends 80 relatively wide conveying surfaces and intermediate such wide surfaces having a plurality of separate narrow conveying surfaces arranged in parallel, there being sufficient space between the narrow surfaces to permit 85 an operator to stand and work between them, means for reciprocating said table to convey material theralong, the space between the separate narrow portions being open so that the operator may stand between them and not be interfered with by the reciprocation 90 of the table.

3. A picking table comprising a relatively 95 wide conveying surface and means for conveying material thereto, a plurality of relatively narrow conveying branches diverging from said wide portion, the surfaces of said branches where they diverge being downwardly and outwardly inclined to assist in guiding the material. 90

4. A picking table comprising a relatively 100 wide conveying surface and means for conveying material thereto, a plurality of relatively narrow conveying branches diverging from said wide portion, the surfaces of said branches where they diverge being downwardly and outwardly inclined to assist 105 in guiding the material, the branches after divergence being parallel one with the other, their surface where they are parallel being substantially level.

5. A picking table comprising a relatively 110 wide conveying surface and means for conveying material thereto, a plurality of relatively narrow conveying branches diverging from said wide portion, the surfaces of said branches where they diverge being downwardly and outwardly inclined to assist in 115 guiding the material there being a sudden change in level at the boundary line between the inclined and the level conveying surfaces.

6. A picking table comprising a relatively 120 wide conveying surface and means for conveying material thereto, a plurality of relatively narrow conveying branches diverging from said wide portion, the surfaces of said branches where they diverge being downwardly and outwardly inclined to assist 125 in guiding the material, the branches after divergence being parallel one with the

other, their surface where they are parallel being substantially level, there being a sudden change in level at the boundary line between the inclined and the level conveying 5 surfaces.

7. A picking table having at both ends single relatively wide conveying surfaces and intermediate such wide surfaces having a plurality of separate narrow conveying 10 surfaces arranged in parallel, a screen member in the conveying surface, and a conveying platform beneath the first mentioned platform and adapted to catch and convey the material which passes through the 15 screen.

8. A picking table having at both ends relatively wide conveying surfaces and intermediate such wide surfaces having a plurality of separate narrow conveying 20 surfaces arranged in parallel, there being sufficient space between the narrow surfaces to permit an operator to stand and work between them, a screen member in the conveying surface, and a conveying platform beneath the first mentioned platform and adapted to catch and convey the material which passes through the screen. 25

9. A picking table having at both ends relatively wide conveying surfaces and intermediate such wide surfaces having a plurality of separate narrow conveying surfaces arranged in parallel, means for reciprocating 30 said table to convey material therealong, a screen member in the conveying surface and a conveying platform beneath the first mentioned platform and adapted to catch and convey the material which passes through the screen. 35

10. A picking table having at both ends relatively wide conveying surfaces and intermediate such wide surfaces having a plurality of separate narrow conveying surfaces arranged in parallel, there being sufficient 40 space between the narrow surfaces to permit an operator to stand and work between them, means for reciprocating said table to convey material therealong, the space between the separate narrow portions being open so that the operator may stand between them and not be interfered with by the reciprocation of the table, a screen member in the conveying surface, and a conveying platform beneath the first mentioned platform and adapted to catch and convey the material 45 which passes through the screen. 50

11. A picking table having at both ends relatively wide conveying surfaces and intermediate such wide surfaces having a plurality of separate narrow conveying surfaces 55 arranged in parallel, a plurality of screening surfaces in the upper conveying surface, at least one of them in the wide portion and at least one of them in the branch portion and a lower conveying member adapted to

catch and convey the material which passes 60 through said screen.

12. A picking table having at both ends relatively wide conveying surfaces and intermediate such wide surfaces having a plurality of separate narrow conveying surfaces 70 arranged in parallel, there being sufficient space between the narrow surfaces to permit an operator to stand and work between them, a plurality of screening surfaces in the upper conveying surface at least one of them in 75 the wide portion and at least one of them in the branch portion and a lower conveying member adapted to catch and convey the material which passes through said screen.

13. A picking table having at both ends 80 relatively wide conveying surfaces and intermediate such wide surfaces having a plurality of separate narrow conveying surfaces arranged in parallel means for reciprocating said table to convey material therealong, 85 a plurality of screening surfaces in the upper conveying surface at least one of them in the wide portion and at least one of them in the branch portion and a lower conveying member adapted to catch and convey the material 90 which passes through said screen.

14. A picking table having at both ends relatively wide conveying surfaces and intermediate such wide surfaces having a plurality of separate narrow conveying surfaces 95 arranged in parallel, there being sufficient space between the narrow surfaces to permit an operator to stand and work between them, means for reciprocating said table to convey material therealong, the space between the separate narrow portions being open so that the operator may stand between them and not be interfered with by the reciprocation of the table, a plurality of screening surfaces in the upper conveying surface, at least one of them in the wide portion and at least one of them in the branch portion and a lower conveying member adapted to catch and convey the material 100 which passes through said screen. 110

15. A picking table having at both ends, single, relatively wide conveying surfaces, and, intermediate such wide surfaces, and connecting them, a plurality of separate, narrow, conveying surfaces, each having 115 space at either side sufficient to permit an operator to stand and work.

16. A picking table having at both ends, single, relatively wide conveying surfaces, and, intermediate such wide surfaces, and connecting them, a plurality of separate narrow, conveying surfaces, each having space at either side sufficient to permit an operator to stand and work and means for reciprocating said table to convey material therealong. 120 125

Signed at Chicago county of Cook and State of Illinois, this 16th day of April 1920.
